UNITED STATES PATENT OFFICE.

JOHN DEAM KNEEDLER AND JOHN C. MCGARR, OF SIOUX CITY, IOWA.

ROAD-BED EQUIPMENT.

No. 919,183.

Specification of Letters Patent.

Patented April 20, 1909.

Application filed November 10, 1908. Serial No. 461,929.

To all whom it may concern:

Be it known that we, JOHN DEAM KNEEDLER and JOHN C. MCGARR, citizens of the United States, residing at Sioux City, in 5 the county of Woodbury and State of Iowa, have invented certain new and useful Improvements in Road-Bed Equipment; and we do hereby declare the following to be a full, clear, and exact description of the invention, such as will enable others skilled in the art to which it appertains to make and use the same.

Our invention relates to new and useful improvements in road bed equipment and 15 of that class adapted more particularly for constructing railway tracks, etc., and our object is to provide a combination cross tie and supporting means therefor, formed of plastic material and metal.

20 A further object is to provide a suitable cushioning device, whereby the metallic parts are prevented from destroying the parts formed of plastic material.

25 A further object is to provide means in the plastic parts for receiving and holding the spikes employed for securing the rails.

A further object is to provide suitable supporting and bracing means for holding the rails from spreading.

30 Other objects and advantages will be hereinafter referred to and more particularly pointed out in the claims.

In the accompanying drawings which are made a part of this application, Figure 1 35 is a top plan view of a fragment of a road bed showing our invention applied to use. Fig. 2 is a transverse sectional view illustrating the invention in detail. Fig. 3 is an enlarged sectional view of the securing device. Fig. 4 is a perspective view of a length of trackway, showing a slightly modified means for securing the track rails in position. Fig. 5 is a detail view partly in section and partly in full lines of one of the 45 track rails and the supporting and securing means therefor, and, Fig. 6 is an elevation of that form of bracing member shown in Figs. 4 and 5.

Referring to the drawings in which similar reference numerals designate corresponding parts throughout the several views, 1 indicates the supporting sleepers or pots, which are preferably formed of plastic material and arranged in pairs, each pair being secured together and spaced apart by means of a metallic cross tie 2, the ends of

the cross tie entering grooves 3 in the sleepers and resting upon cushions 4 placed in the bottom of said grooves, said cushions being formed of any desired yielding material and adapted to receive the jar occasioned by trains passing over the road-way. The sleepers 1 are provided with vertical openings 5 in which are adapted to extend metal tubes 6, the lower ends of the tubes being 60 threaded as at 7 to engage burs 8 embedded in the sleepers 1, whereby said tubes are securely held in position in the sleepers. The upper ends of the tubes 6 terminate 65 flush with the bottom of the grooves 3 and are positioned below openings 9 in the cross tie 2, so that the spikes 10 employed for holding the rails 11 against displacement, will enter said tubes.

The spreading of the rails is effectually 70 prevented by providing brace members 12 along the outer edges of the rails, said braces having their inner ends arranged to extend over the base of the rail, while the body portions and opposite ends thereof are provided with openings to receive the spikes 10, the openings in the braces registering with the openings in the tie 2.

The spikes 10 are securely held in the openings 9 and the heads thereof in engagement 75 with the rail and securing devices by inserting cores in the tubes 6, said cores being preferably formed of wood so that when the spikes are driven therein, the wood will expand sufficiently to admit the spikes, but in view of 80 the snug fit of the cores in the tubes, the spikes will be firmly gripped by the wood and prevented from casually leaving the openings or rising a sufficient distance to loosen the rail.

In view of the fact that the tubes 6 are 85 removably secured in the openings in the sleepers, said tubes may be readily removed and a new core inserted therein and it will further be seen that should the heads become broken from the spike, said spike may be driven entirely through the core and a new spike inserted in its place. It will likewise be seen that if desired, a cushioning plate 13^a may be introduced between the 90 base of the rails 11 and the upper face of the tie 2, in which event the force of the jar occasioned by the train, will be entirely eliminated from the sleepers.

In Figs. 4, 5 and 6 we have shown a 110 slightly modified form of construction, in that we have provided a chair 14 for the

2

rails, the base 15 of which rests in a cavity 16 formed in the upper face of the sleeper 1, said base having a groove 3^a to receive the end of the cross tie 2, said base also having openings 9^a to receive the spikes 10. At the outer end of the base 15 and at each edge thereof, are inwardly and upwardly extending arms 17, the contour of said arms being such as to engage the face of the flange and the face of the web of the rail, said arms forming a rigid brace for the rails and preventing the rails from spreading. These brace arms are adapted to be used more particularly when a curve is encountered in the road-way and are to replace the usual form of brace blocks commonly used in railway construction. In this form of device a cushion plate 4^a is introduced under the base of the chair 14 to receive the jar 1, 2 and 3.

What we claim is:

1. In a road bed equipment, the combination with plastic sleepers having channels and vertically disposed openings therein; of a metallic tie adapted to secure said sleepers in pairs, said tie having openings therein registering with the openings in the sleepers, rails resting on said sleepers and tie, spikes adapted to hold said rails in position on the sleepers, tubes adapted to enter the openings in the sleepers, means to removably secure the tubes in the openings and additional means carried by the tubes to engage said spikes and hold the same in position.

2. In a road bed equipment, the combination with plastic sleepers having vertical openings therein and grooves in the upper faces thereof; of rails adapted to rest on said sleepers, a metallic tie connecting said sleepers in pairs, a chair for each sleeper having brace arms thereon and grooves to receive the tie, spikes adapted to hold the rails and chairs in position on the sleepers and removable means seated in the vertical openings in the sleepers to engage the lower ends of the spikes and hold the same in engagement with the rails.

3. In a road bed equipment, the combination with sleepers having vertical openings therein, a tube adapted to enter each opening, a bur embedded in the sleeper adapted to engage and hold the tubes and a wooden core within the tubes.

4. In a road bed equipment, the combination with track rails; of plastic sleepers to support said rails, said sleepers having cavities, rail chairs adapted to enter said cavities and receive the rails, a cushioning plate below said chairs, said chairs having inwardly and upwardly extending arms adapted to engage parts of the rails and means to secure the rails and chairs to the sleepers.

In testimony whereof we have signed our names to this specification in the presence of two subscribing witnesses.

JOHN DEAM KNEEDLER.
JOHN C. McGARR.
